CLAIM

The ornamental design for a tarot card board, as shown and described.

DESCRIPTION

FIG. 1 is a top view of an embodiment of a tarot card board according to the present invention;

FIG. 2 is a bottom view of the tarot card board of FIG. 1;

FIG. 3 is a front view of the tarot card board of FIG. 1;

FIG. 4 is a rear view of the tarot card board of FIG. 1;

FIG. 5 is a right side view of the tarot card board of FIG. 1; and,

FIG. 6 is a left side view of the tarot card board of FIG. 1. The broken line showing of corner pieces and board legs are included for the purpose of illustrating portions of the "article" and forms no part of the claimed design.
